FIG. 1

FIG. 2

FIG. 3

FIG. 4

FIG. 6

FIG. 7

FIG. 8

FIG. 9

FIG. 10

FIG. 5

FIG. 11

FIG. 1 is a top plan view of a combined jug and bottle embodying my new design;

FIG. 2 is an end elevational view;

FIG. 3 is a side elevational view, the opposite side being a mirror image of the side shown;

FIG. 4 is an end elevational view looking from the right of FIG. 3 and showing the end opposite that seen in FIG. 2;

FIG. 5 is a fragmental vertical sectional view taken along reference line 5-5 of FIG. 3;

FIG. 6 is a bottom plan view;

FIG. 7 is a top plan view of the jug with the bottle removed therefrom;

FIG. 8 is an end elevational view thereof;

FIG. 9 is a side elevational view thereof, the opposite side being a mirror image of the side shown;

FIG. 10 is an end elevational view looking from the right of FIG. 9 and showing the end opposite that shown in FIG. 8; and

FIG. 11 is a bottom plan view of the jug shown in FIGS. 7, 8, 9 and 10.

The ornamental design for a combined jug and bottle, as shown and described.
